CLAIM

The ornamental design for a glass joint with plunger, substantially as shown and described.

DESCRIPTION

FIG. 1 is a perspective view of the glass joint with the plunger in an installed position;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is an exploded perspective view of the glass joint with plunger thereof;

FIG. 9 is an exploded right side view thereof;

FIG. 10 is an exploded left side view thereof;

FIG. 11 is an exploded top view thereof;

FIG. 12 is an exploded bottom view thereof;

FIG. 13 is a front view thereof; and,

FIG. 14 is a rear view thereof.

The broken lines in the drawings depict portions of the glass joint with plunger that form no part of the claimed design.
